CLAIM

The ornamental design for a fixed broadhead, as shown and described.

DESCRIPTION

FIG. 1 is a perspective view of a fixed broadhead, showing my new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is an exploded perspective view thereof.

The dash-dot broke lines in the drawings depict projection lines and form no part of the claimed design.
